UNITED STATES PATENT OFFICE

WILLIAM E. SKELTON, OF LAGRANGE, GEORGIA

WASHING MACHINE

Application filed April 16, 1928. Serial No. 270,419.

The object of this invention is to provide an efficient machine by the use of which clothes may be rapidly and thoroughly cleansed and subjected to the direct action of 5 hot water or steam directed thereonto in a plurality of fine streams or jets. The invention also includes means whereby the clothes will be subjected to an oscillatory movement transverse to their line of travel 10 without injury while passing through the machine and will also be subjected to an efficient rubbing action. The invention resides in certain novel features of construction and arrangement which will be hereinafter first 15 fully described and then more particularly defined in the appended claims.

The invention is illustrated in the accompanying drawings, in which

Figure 1 is a top plan view of the machine 20 with the covers removed;

Fig. 2 is a central longitudinal vertical section through the machine;

Fig. 3 is a side elevation of the same;

Fig. 4 is a central transverse vertical sec- 25 tion;

Fig. 5 is a detail view illustrating the manner of mounting the wringer rolls;

Fig. 6 is a detail section on the line 6—6 of 30 Fig. 2;

Fig. 7 is a detail section of the form of bearing which will preferably be employed;

Fig. 8 is a central transverse section through the parts shown in Fig. 7;

Fig. 9 is a detail view of a cover plate, and

Fig. 10 is a detail view of a part of the driving mechanism.

In carrying out the invention, there is provided a tub 1 which may be of any approved form having sufficient strength and durability and supported in any convenient manner, as by legs 2. The tub is preferably rather shallow, as shown in Fig. 2, and includes covers 3 which will prevent the water, suds and steam escaping through the top of the tub and will retain the same therein so that they will act thoroughly upon the clothes. Each cover 3 comprises a plate having notches 4 at its inner edge whereby it is adapted to fit around the rubber hangers and 45 at its outer corners is formed with recesses 50

5 whereby it is adapted to fit around the standards or posts in which the bearings for the wringer rolls are mounted. At each end of the tub 1 secure posts or standards 6 having vertical slots 7 formed in their upper portions, as shown most clearly in Fig. 5, and in the said slots are slidably mounted bearing blocks 8 receiving the trunnions 9 of upper wringer rolls 10, while the trunnions 11 of lower wringer rolls 12 are fitted in the respective standards or posts below the slots. Mounted in the upper end of each standard 55 is an adjusting stop screw 13 which is adapted to bear against the top of the bearing block 8 and thereby limit the upward movement of the same, and these several screws can respectively be adjusted so as to hold the upper roll to the clothes with any desired degree of pressure. Immediately adjacent the wringer rolls, at the outer sides thereof, 60 an apron or drain board 14 is carried by the end wall of the tub so that any water which may drip or be expelled from the clothes 65 passing from between the rollers at the outer sides thereof will be deflected back into the 70 tub.

Referring more particularly to Figs. 2 and 3, it will be noted that the bottom of the tub inclines upward from its central portion toward each end and extending parallel with the bottom of the tub are lower rollers 15 forming a continuous series extending from one pair of wringer rolls to the other pair of wringer rolls. These lower rubbing or presser rolls are each provided with trunnions or axles fitted in bearing boxes 16 secured on the side walls of the tub and between said bearing box and the working portion of each roll a sprocket gear 17 is secured upon the axle or trunnion. Sprocket chains 18 are trained about the sprockets 17 in series, as will be understood on reference to Fig. 1 so that all the lower rolls will be caused to rotate in unison. The rolls are formed upon their peripheries with annular grooves 19 which are disposed obliquely or spirally and the grooves upon adjacent rolls are arranged reversely relative to each other. As a result of this reverse arrangement, the 75 rolls in operation not only act to feed the 80

clothes through the tub but also impart there-to a transverse movement alternately in op-posite directions as the clothes pass through the tub. It will be observed upon reference to Fig. 2 that the outermost roll at each end 5 of the series of rolls 15 is disposed approxi-mately in the same horizontal plane with the adjacent lower wringer roll and the series of rolls follows the form of the bottom of 10 the tub and is disposed parallel therewith throughout the length of the machine. Sec-ured to the side walls of the tub over the in-15 clined end portions of the series of rolls 15 are rails or guide blocks 20 in which are se-cured guide pins 21 extending downwardly 20 from the rails to pass between or through the sub-jacent supports for the lower rolls and slidably mounted upon these pins are carriers 22 in the form of bars arranged substantially parallel with the rails 20 and of similar form 25 and each forming bearings for the journals or trunnions 23 of upper rollers 24. The rollers 24 are similar in form and dimensions to the rolls 15 and have annular grooves 25 which are arranged reversely to the grooves 30 in the immediately subjacent rolls 15 so that clothes received between the two sets of rolls will be effectually engaged and not only fed through the machine but also shifted trans-35 versely in opposite directions alternately so as to be subjected to a thorough rubbing ac-tion. Expansion springs 26 are disposed be-tween the rails 20 and the respectively sub-40 jacent carrier bars 22 and act upon said bars 35 to yieldably hold the upper rolls toward the lower rolls and thereby maintain the desired pressure upon the clothes without binding 45 upon them so tightly that the clothes will be damaged.

40 Obviously, the central portion of the se-ries of lower rolls will be disposed substan-tially horizontally. To cooperate with the central portion of the series of rolls, I pro-50 vide a rubber comprising a plurality of rolls 45 27 which, like the rolls 15 and 24, are pro-55 vided with annular grooves arranged oblique-ly or in spirals and in reversed relation to the grooves upon adjacent rolls. These rolls 27 have their trunnions or axles mounted in 60 end blocks 28 which are connected by cross 65 bars 29, and upon the cross bars at the ends thereof are secured bearing plates or caps 30 carrying pivot pins or bolts 31 upon which 65 are pivotally mounted the lower ends of 70 hangers 32, said hangers passing through the 75 notches 4 of the covers 3 when the parts are 80 all assembled and the machine is in operation. In their upper portions, the hangers are each 85 formed with slots 33 and 34, as shown clearly 90 in Figs. 2 and 3, the lower slots receiving a 95 fulcrum rod 35 which is secured in the side 100 walls of the tub and extends entirely across 105 the tub, this arrangement permitting vertical 110 movement of the hangers and also causing 115 them to oscillate or rock about the rod as a 120

center. The upper slots 34 of the hangers re-125 ceive the crank portions 36 of a driving shaft 130 37 so that, as the shaft is rotated, the cranks 135 will impart an oscillatory movement to the 140 hangers and thereby cause the rubber rollers 145 27 to move back and forth over the clothes and 150 by their travel over the clothes held upon 155 the central rollers 15 will loosen any particles 160 of dirt which may be clinging to the clothes 165 so that as the clothes emerge from the tub 170 they will be thoroughly cleaned, it being 175 understood that the action of the water and 180 steam delivered into the tub is to remove all 185 surface dirt and also drive from the clothes 190 any grease or other matter which may have 195 collected in the fabric. To minimize the fric-tional wear between the cranks 36 and the 200 walls of the respective slots 34 in the hangers, 205 bushings 38 are fitted around the cranks to 210 extend through the slots, as will be readily 215 understood.

The ends of the driving shaft 37 extend 220 through standards 39 secured to and rising 225 above the sides of the tub and are journaled 230 in bearing boxes 40 carried by said stand-235 ards, as will be understood. Upon one end of 240 the driving shaft are mounted loose pulleys 245 41 and a fast pulley 42 between the loose 250 pulleys, belts 43 being provided to cooperate 255 with the pulleys and transmit motion there-260 to from any convenient source of power, it 265 being noted that one of the belts is straight 270 and the other is crossed, and the driving 275 shaft will be driven in one or the other di-280 rection accordingly as one or the other belt 285 is shifted onto the fast pulley. When the 290 machine is not in operation, the belts will be 295 trained around the respective loose pulleys, 300 as shown in Fig. 4, but when the machine is 305 to be used, the belts are shifted so that one 310 or the other will pass around the fast pulley, 315 and to accommodate the belts in either of 320 their shifted positions, the loose pulleys are 325 twice as long as the fast pulley or the width 330 of the belts. At the opposite end of the driv-335 ing shaft, I secure thereto sprocket gears 44 340 about which are trained sprocket chains 45 345 which pass from the respective gears to the 350 ends of the tub and are there trained around 355 sprocket pinions 46 secured upon the outer 360 extended ends of the trunnions of the outer-365 most rollers 15 whereby rotation is imparted 370 to the pinion 17 on said trunnion and the 375 chains 18 driven. The last-mentioned trun-nions carry pairs of sprocket pinions outside 380 the tub and the inner sprocket of each pinion 385 is operatively connected by a sprocket chain 390 47 with a sprocket pinion 48 on the trun-nion of the adjacent lower wringer roll. It 395 will thus be seen that the rubber is oscillated, 400 the lower rollers 15 are positively driven, and 405 the lower wringer rolls are also positively 410 driven from the single driving shaft, and the 415 wringer rollers 15 and the lower rubbing 420 rolls are rotated in the same direction.

To shift the driving belts 43, a shifting bar 49 is mounted transversely and slidably in the upper ends of the standards 39 and carries at one end a yoke 50 provided with slots 51 engaging around the respective belts whereby if endwise movement be imparted to the shifting bar the belts will be likewise shifted so that they will be set in a desired position to cause rotation of the driving shaft in either direction or to stop the operation of the machine. Mounted upon that standard 39 more remote from the driving pulleys is a vertically disposed rocking arm 52 provided at its upper end with a crank 53 which extends over the shifting bar 49 and is engaged in a socket or recess 54 in said bar so that, when the arm is rocked, the crank 53 will impart an endwise movement to the shifting bar. At its lower end the rocking arm 52 is provided with a laterally extending crank 55 which forms a convenient handle whereby the arm may be rocked by an attendant standing adjacent the center of the tub. As it is frequently desirable to control the operation from the ends 25 of the tub, a rod 56 is slidably supported in any convenient manner upon the side of the tub and extends from end to end thereof, being provided with any convenient form of handle 57 at each end. Adjacent its center, 30 this shifting rod 56 is formed with an eye or loop, indicated at 58, which is engaged around the crank 55 so that any movement imparted to the rod 56 will be transmitted directly to said crank and through the same to 35 the rocking arm 52.

Secured in the sides of the tub adjacent the ends thereof and over the presser rollers 24 are supply pipes 59 each of which is closed at one end and is provided at intervals with 40 depending nozzles or jets 60 directed toward the subjacent rollers 24, as shown clearly in Fig. 2. The open ends of these pipes 59 are coupled into pipes 61 which are mounted on the side of the tub and extend to a boiler (not 45 shown) to lead steam and hot water into the tub, and in the said pipes 61 are mounted valves 62 whereby the flow of steam and hot water may be cut off or regulated.

In Figs. 7 and 8, I have shown in detail the 50 structure of the bearings in which the several rotating parts will be mounted, the details of this structure not appearing in the other figures, owing to the reduced scale of the latter. In Figs. 7 and 8, the numeral 63 designates a 55 shaft or trunnion, as, for instance, the trunnion of one of the rollers 15. Within the bearing block 64, the trunnion has fitted thereon bushings 65 and around said bushings rollers 66 are mounted, as shown, packing washers 67 being provided between the ends of the rollers and the side plates 68 of the bearing, and these washers may be provided with 60 openings receiving end trunnions of the rollers so as to hold the rollers in spaced relation. 65 In the upper side of the bearing block 64 is

mounted an oil cup 69 and a duct 70 leads from said oil cup through the bearing block to the bearing rollers so as to supply lubricant to the latter; and it will be readily noted that the packing washers 67 prevent the lubricant leaking from the bearing box so as to reach and soil the clothes. 70

From the foregoing description, taken in connection with the accompanying drawings, it will be seen that I have provided a very 75 efficient and easily operated machine whereby clothes may be rapidly and thoroughly cleaned. As the main driving shaft is rotated, the hangers or pitmen suspended thereon will oscillate the rubber over the 80 clothes and the slotted construction of the hangers permits the rubber to readily accommodate itself to the bulk of the clothes passing through the machine. To lighten the work, it is desirable that the clothes be 85 permitted to soak within a vessel containing water and soap or some other cleaning agent before being passed through the washing machine. The wet clothes will be caused to enter the tub between the wringer rolls at one 90 end thereof and surplus water will be thereby squeezed therefrom and this surplus water will be caught by the adjacent drain board 14 and directed into the tub. From the wringer rolls, the clothes are passed to and 95 between the adjacent upper and lower rolls 24 and 15 and will be fed through the machine by the positive rotation of the lower rolls. The upper rolls will press yieldably 100 upon the clothing so that it will be positively engaged by the grooved circumferences of the opposed rolls and will, consequently, be given a transverse vibratory movement as it passes through the tub so that loose surface dirt 105 will be removed. At the center of the tub, the clothes will be acted upon by the rocking rubber and will then pass between the second set of rolls 24 and 15 to be discharged between the second wringer rolls. The hot water and steam which enters the tub over the 110 respective yieldably mounted upper rolls will saturate the clothing and drive therefrom any dirt or other matter which may have penetrated the fabric so that, when the clothes are finally drawn from the tub, they 115 will be thoroughly cleaned. The dirt removed from the clothes will, of course, settle at the bottom of the tub, and a drain valve 71 is provided to draw off the dirty water after the washing operation is completed. 120

Having thus described the invention, I claim:

1. A washing machine comprising a tub, a series of rolls mounted transversely in the tub and extending from end to end thereof, 125 said rolls having obliquely disposed annular grooves in their peripheries, the grooves in adjacent rolls being relatively reversely arranged, series of yieldably supported rolls in the respective end portions of the tub above 130

and cooperating with the first-mentioned rolls to engage clothes to be washed, and means for positively rotating the first-mentioned rolls, the yieldably mounted rolls being also provided with obliquely disposed annular grooves in their peripheries with the grooves in each roll reversed relative to the adjacent roll in the same series and the respectively subjacent roll in the lower series.

- 5 10 2. A washing machine comprising a tub, a series of transversely disposed feeding and rubbing rolls arranged in the tub and extending from end to end thereof parallel with the bottom of the tub, means for positively 15 rotating said rolls, carriers extending longitudinally of the tub and arranged over the rolls at the respective ends of the tub, rails secured to the sides of the tub above the carriers, series of rolls arranged in the respective 20 carriers having means to cooperate with the first-mentioned rolls in engaging and agitating clothes to be washed, and expansion springs disposed between the rails and the carriers and bearing thereon to yieldably 25 hold the carriers and the rolls therein toward the lower rolls.

3. A washing machine comprising a tub, a series of transversely arranged feeding and rubbing rolls arranged in the tub and extending from end to end thereof, means for 30 positively rotating said rolls, a crank shaft supported over the tub at the center thereof, a fulcrum rod secured transversely in the tub at the center thereof and adjacent the top of 35 the same, hangers having slotted portions receiving the crank shaft and other slotted portions receiving the fulcrum rod whereby the hangers may move vertically and also oscillate about the fulcrum rod, means for rotating 40 the shaft, a frame pivotally attached to the lower ends of the hangers, and a plurality of rubbing and feeding rolls carried by said frame above and cooperating with the first-mentioned rolls in engaging and agitating articles to be washed.

45 In testimony whereof I affix my signature.
WILLIAM E. SKELTON. [L. s.]
